UNITED STATES PATENT OFFICE.

HENRY W. BOWMAN, OF BARBOURSVILLE, KENTUCKY.

BOTTLE-WASHER.

No. 831,261.

Specification of Letters Patent.

Patented Sept. 18, 1906.

Application filed June 29, 1905. Serial No. 267,600.

To all whom it may concern:

Be it known that I, HENRY W. BOWMAN, a citizen of the United States, residing at Barboursville, in the county of Knox and State of Kentucky, have invented a new and useful Bottle-Washer; and I do hereby declare the following to be a full, clear, and exact description of the invention, such as will enable others skilled in the art to which it appertains to make and use the same.

This invention relates to bottle-washing machines, and has for its principal object to provide a machine of simple and economical construction by which bottles of any type may be rapidly cleansed.

With this and other objects in view, as will more fully appear when the nature of the invention is more fully understood, the same consists in the novel construction and arrangement of parts hereinafter described, illustrated in the accompanying drawings, and particularly pointed out in the appended claims.

In the drawings, Figure 1 is a plan view of the bottle-washing machine constructed in accordance with the invention. Fig. 2 is a longitudinal sectional view of the same on the line 2 2 of Fig. 1. Fig. 3 is a transverse section of the machine on the line 3 3 of Fig. 1. Fig. 4 is a detail perspective view of the main reciprocating carriage and the tilttable frame supported thereby. Fig. 5 is a detail sectional view, on a larger scale, of the bottle-carrier and a portion of the tilttable frame.

Similar numerals of reference are employed to designate corresponding parts throughout the several figures of the drawings.

The various working parts of the machine are supported in a suitable frame 1, having side members 2, the upper portions of which are provided with longitudinal slots 3, that are arranged for the reception of studs 4 and 6, projecting from the opposite side bars of a reciprocating carriage 5.

The carriage 5 is in the form of an open rectangular frame and is provided at one end with pivot-ears 36, carrying a short horizontal shaft 35, which serves to connect the lugs to the inner ends of a pair of links 37. The outer ends of the links are connected to a crank-pin 38, carried by the main operating-shaft 39, which may be operated manually by a crank 42 or may be driven by power through a belt-wheel 40, a clutch 41 being pivotally employed in the latter case to connect the belt-wheel to the shaft.

Arranged within the reciprocating carriage 5 is a tilttable frame, the opposite side bars of which are rigidly secured to the studs 6. These studs project through suitable openings in the side bars of carriage 5 and at their outer ends carry arms 7, that are connected by helical tension-springs 8 to fixed eyes or studs on the main frame, the function of the springs being to hold the frame 10 within and in parallel relation with the side bars of the carriage 5. The studs 6 form trunnions or pivots on which the tilttable frame may be swung to approximately vertical loading position, and the frame when so adjusted is engaged and held by a catch 32, carried by the free end of a leaf-spring 30.

The tilttable frame 10 is provided with bearings for the reception of a shaft 11, the front end of which projects through a recess 11', formed in the front bar of the carriage 5, and serves by engagement with the bottom of said recess to limit the movement of frame 10 under the influence of the springs. On the shaft 11 is secured a disk 12, having a hub 13, through which passes a set-screw 13', the latter serving to lock the disk in any desired position of adjustment on the shaft. This disk is provided with an annular series of openings 14, the inner walls of which are tapered to form seats for the bottoms of the bottles, as shown more clearly in Fig. 5.

The rear end of the shaft 11 is of somewhat larger diameter than the forward or crank-shaft end and is hollow in order that it may afford a passage for the washing fluid. On this portion of the shaft is secured a disk 15, having an annular series of openings for the reception of cups 16, that are arranged to receive the mouths of the bottles. These cups are provided with annular flanges 16^a, between which and the disk-face are arranged helical compression-springs 16^b, tending to force the cups tightly against the mouths of the bottles, and thus form tight joints therewith. Each cup carries a nozzle 17, that is arranged to enter the mouth of the bottle, and the rear end of each nozzle is connected by a flexible tube 25 to a nipple 25', projecting from and in communication with the hollow portion of the shaft 11, in order to conduct water or other fluid to said nozzles.

The rear portion of the shaft carries a cylindrical casing 21, which communicates with the hollow shaft through openings 20, and a fluid-proof joint is formed at the ends of the casing by the washers 18 and 19, the packing-

rings 26 and 27, and the clamping-nut 28. Projecting from one side of the casing 21 is a nipple 23, which is supported by an arm 23' and is connected by a flexible tube 24 to a 5 source of water-supply.

The forward end of the shaft 11 carries a bevel-pinion 33, that intermeshes with a bevel-gear 34 on the shaft 35, and said bevel-gear is secured to a sprocket-wheel 43, which 10 is connected by a link belt 44 to a sprocket-wheel 45 on the crank-pin 38, so that as the latter revolves rotary movement will be transmitted to the shaft 11 and the bottle-carrying disks.

15 In order to cleanse the exteriors of the bottles, a tank 29 is preferably arranged below the bottle-carrier and the water-level is sufficiently high to insure the immersion of the bottles as they are carried around by the 20 disks.

25 In operation the tiltable frame 10 is thrown up to approximately vertical position, a handle 46 being placed on the frame for convenience in manipulation. The rear 30 end bar of frame is caught and held by the catch 32, and the bottles to be washed are then inserted between the cups 16 and disk 12. The catch 32 is then forced down manually or otherwise, and the springs 8 return the 35 tiltable frame to horizontal position, shaft 11 entering the recess 11' and the bevel-pinion 33 engaging with the bevel-gear 34. On turning the shaft 39 the carriage is reciprocated and at the same time rotary movement is imparted to the shaft 11, so that the bottles will be carried around and successively 40 immersed in the water in tank 9. During this operation water or other fluid may be constantly supplied through the nozzles 17, so that both the exterior and interior of the bottles will be thoroughly cleansed.

I claim—

1. The combination in a bottle-washing machine, of a frame having longitudinal slots, a reciprocating carriage having projecting studs guided in said slots, a tiltable frame secured to one set of studs, and supported thereby, at a point within the carriage, arms secured to the outer ends of said set of studs, springs engaging said arms, and tending to maintain the frame in horizontal position, a catch for engaging the frame, and holding the same in bottle-loading and unloading position, a bottle-carrier supported by the tiltable frame, means for revolving the bottle-carrier, and for reciprocating the carriage. 55

2. In a bottle-washing machine, the combination with a frame, of a reciprocatory carriage supported thereby, and having a recess at one end, a main crank-shaft, links connecting the crank-pin to the carriage, a shaft arranged to form a connection between the links and carriage, a bevel-gear and sprocket-wheel on said shaft, a sprocket-wheel on the crank-pin, a link belt connecting the 60 sprocket-wheels, a tilting frame arranged within the carriage, a shaft journaled in said frame, and provided at one end with a bevel-pinion arranged to intermesh with the bevel-gear, said shaft being arranged to enter the 65 recess at the end of carriage, springs for retaining the tilting frame in horizontal position, and a bottle-carrying means supported by the shaft on the tilting frame. 70

In testimony whereof I have hereto affixed 75 my signature in the presence of two witnesses.

HENRY W. BOWMAN.
